(57) **CLAIM**

The ornamental design for a laundry basket, as shown and described.

DESCRIPTION

Fig. 1.1 is a top, perspective view of a laundry basket.

Fig. 1.2 is a bottom, perspective view of a laundry basket.

Fig. 1.3 is a left elevational view of a laundry basket, the right elevational view being identical to the respective left elevational view of Fig. 1.3.

Fig. 1.4 is a front elevational view of a laundry basket, the rear elevational view being identical to the respective front elevational view of Fig. 1.4.

Fig. 1.5 is a top view of a laundry basket.

Fig. 1.6 is a bottom view of a laundry basket.

Fig. 2.1 is a top, perspective view of a laundry basket.

Fig. 2.2 is a bottom, perspective view of a laundry basket.

Fig. 2.3 is a left elevational view of a laundry basket, the right elevational view being identical to the respective left elevational view of Fig. 2.3.

Fig. 2.4 is a front elevational view of a laundry basket, the rear elevational view being identical to the respective front elevational view of Fig. 2.4.

Fig. 2.5 is a top view of a laundry basket.

Fig. 2.6 is a bottom view of a laundry basket.

Fig. 3.1 is a top, perspective view of a laundry basket.

Fig. 3.2 is a front elevational view of a laundry basket.

Fig. 3.3 is a rear elevational view of a laundry basket.

Fig. 3.4 is a right elevational view of a laundry basket, the left elevational view being a mirror image of the respective right elevational view of Fig. 3.4.

Fig. 3.5 is a top view of a laundry basket.

Fig. 3.6 is a bottom view of a laundry basket.

Fig. 3.7 is a perspective view with opened lid of a laundry basket.

Fig. 3.8 is another perspective view with opened lid of a laundry basket

(Continued)

The broken lines shown in the drawings illustrate unclaimed portions and form no part of the claimed design.

1 Claim, 20 Drawing Sheets
